UNITED STATES PATENT OFFICE.

HERBERT G. UNDERWOOD, OF STAMFORD, CONNECTICUT, ASSIGNOR TO
H. H. FRANKLIN MANUFACTURING COMPANY, OF SYRACUSE, NEW
YORK, A CORPORATION OF NEW YORK.

CASTING APPARATUS.

SPECIFICATION forming part of Letters Patent No. 777,571, dated December 13, 1904.

Original application filed June 17, 1897. Renewed January 11, 1900, Serial No. 1,145. Divided and this application filed December 8, 1902. Serial No. 134,430. (No model.)

To all whom it may concern:

Be it known that I, HERBERT G. UNDERWOOD, of Stamford, in the county of Fairfield and State of Connecticut, have invented a certain new and useful Casting Apparatus, of which the following is a specification.

The invention forming the subject-matter of this present application is divisional of my prior application, filed June 17, 1897, renewed January 11, 1900, Serial No. 1,145, and comprises certain novel combinations and constructions in casting apparatus, as hereinafter fully described, and pointed out in the claims.

The accompanying drawings illustrate an apparatus designed and chosen for explanation of this invention.

In the drawings, Figure 1 is a side elevation, partly in section, of the apparatus; and Fig. 2 is a front elevation, partly broken away, of a portion of parts seen in Fig. 1.

A is a melting-pot or other source of supply for the material to be cast, said part A being shown as having a top or cover B.

C is a cylinder or chamber supported by the top or cover B within the pot A and the molten material therein and provided with inlet and outlet ports c c'.

D is a plunger actuated by a lever d for forcing the material from the cylinder or chamber C through the outlet-port c', and E is a substantially upright exit-port or nozzle communicating with the port c'.

The parts thus far described comprise the means for supplying the material to be cast, and are each of any suitable or desirable form, size, and construction. The remaining parts of the apparatus form the mold supporting and manipulating means.

In the illustrated embodiment of this invention F is a supporting member, G a mold, and J a clamping member. As shown, the member F is pivoted to the top or cover B by a horizontal pivot F' and is provided with a port or orifice f for registering with the exit-port or nozzle E and with means, as a handle f', for rocking the member F on its pivot F' relatively to the exit-port E and

alternately presenting the port or orifice f to the exit-port or nozzle E and moving the same from said port E. The handle f' may, however, be dispensed with and any other part fixed to the supporting member F, as the upper end of the standard rising from said supporting member may be used as a handle.

The mold G is composed of any desirable number of sections or parts, (here shown as two,) is mounted directly on the supporting member F, and is preferably provided with an ingate g, opening from the face of the mold opposed to the supporting member F and normally registering with the port or orifice f. During the entrance of the material to be cast said mold is firmly pressed rectilinearly or in a right line toward the opposing face of the member F and the exit-port E by the clamping member J and the movable means connected thereto.

One end of the clamping member J is formed with a guide movable along a standard H, rising from the supporting member F, and its other end is out of direct engagement with the standard and connected to the contiguous section of the mold. An arm K projects laterally from the free end of the standard H and forms the pivot for a lever K', having one end connected by a link K² to the clamping member J and its other end connected by a link K³ to a part K⁴, fixed relatively to the exit-port E. When the clamping member J is in its operative position, the pivot l for connecting the lever K' and the link K² is aligned with the arm or pivot K and the pivot for connecting the other end of the link K² to the clamping member J, thus firmly locking said member J in position during the entrance of the material to be cast.

In the use of this invention the two sections or parts of the mold G are detachably engaged, respectively, with the supporting and clamping members F J. The supporting member F is swung on its pivot F' for presenting the port f to the exit-port or nozzle E to permit the entrance to the mold of the material

to be cast, and during the entrance of said material the clamping member J firmly presses the mold as a whole toward the contiguous face of the supporting member F and the exit-
5 port or nozzle E, and the pivot l locks the clamping member J in its operative position. After the formation of the cast article in the mold the supporting member F is rocked on its pivot to withdraw the port f from the
10 exit-port or nozzle E, and during the movement of the supporting member the part K' causes the lever K' to be automatically rocked on the pivotal arm K, since the part K is moved substantially vertically, thus moving
15 the clamping member J from the supporting member F and separating the sections of the mold to facilitate the removal of the cast article. These several operations can obviously be completed with minimum effort and maxi-
20 mum rapidity.

The construction and operation of my casting apparatus will now be readily understood upon reference to the foregoing description and the accompanying drawings, and it will
25 be obvious that more or less change may be made in the construction and arrangement of the parts thereof without departing from the spirit of my invention.

Having thus fully described my invention,
30 what I claim as new, and desire to secure by Letters Patent, is—

1. In a casting apparatus, a source of supply for the material to be cast, an exit-port for communicating with the source of supply, a
35 mold having an ingate for communicating with the exit-port, a supporting member for the mold movable relatively to the exit-port, means for forcing the material from the exit-port through the ingate into the mold, a clamping member movable toward and from the supporting member, and movable means connected to the clamping member for actuating the same automatically, substantially as and for the purpose described.

45 2. In a casting apparatus, a source of supply for the material to be cast, an exit-port for communicating with the source of supply, a mold having an ingate for communicating with the exit-port, a supporting member for
50 the mold movable relatively to the exit-port, means for forcing the material from the exit-port through the ingate into the mold, a clamping member movable toward and from the supporting member, a part fixed relatively to the exit-port, and movable means connected to the clamping member and said part for automatically actuating the clamping member when the supporting member is operated, substantially as and for the purpose described.

3. In a casting apparatus, a source of supply 60 for the material to be cast, an exit-port for communicating with the source of supply, a mold having an ingate for communicating with the exit-port, a supporting member for the mold movable relatively to the exit-port, 65 means for forcing the material from the exit-port through the ingate into the mold, a clamping member movable toward and from the supporting member, a lever connected to the supporting and clamping members, and means 70 connected to the lever for causing the same to be actuated automatically when the supporting member is operated, substantially as and for the purpose set forth.

4. In a casting apparatus, a source of supply 75 for the material to be cast, an exit-port for communicating with the source of supply, a mold having an ingate for communicating with the exit-port, a supporting member for the mold movable relatively to the exit-port, means 80 for forcing the material from the exit-port through the ingate into the mold, a clamping member movable toward and from the supporting member, a lever connected to the supporting member, means connecting the lever 85 to the clamping member, and a part fixed relatively to the exit-port and connected to the lever for causing the same to be actuated automatically when the supporting member is operated, substantially as and for the purpose described.

5. In a casting apparatus, a source of supply for the material to be cast, an exit-port for communicating with the source of supply, a mold having an ingate for communicating 95 with the exit-port, a supporting member for the mold movable relatively to the exit-port, a standard fixed relatively to the movable supporting member, means for forcing the material from the exit-port through the ingate 100 into the mold, a clamping member having one end provided with a guide movable along the standard and its other end out of direct engagement with the standard and connected to the mold, an arm projecting laterally from the standard, and movable means between the clamping member and said arm for moving the clamping member, substantially as and for the purpose set forth.

In testimony whereof I have hereunto signed my name, in the presence of two attesting witnesses, at New York, in the county of New York, in the State of New York, this 4th day of December, 1902,

HERBERT G. UNDERWOOD.
